SAFETY PIN HOLDER

Filed July 25, 1932

UNITED STATES PATENT OFFICE

ALBERT HAGEL, OF NEWARK, NEW JERSEY, ASSIGNOR TO CONSOLIDATED SAFETY PIN COMPANY, OF BLOOMFIELD, NEW JERSEY, A CORPORATION

SAFETY PIN HOLDER

Application filed July 25, 1932. Serial No. 624,540.

This invention relates to improvement in safety-pin holders, that is, a holder to which a number of safety pins may be attached and thereby forming a retail unit, the object of 5 the invention being to provide a holder which may readily be struck from sheet metal and to which a number of safety pins may be readily attached, and the invention consists in the construction as hereinafter described and 10 particularly recited in the claims.

In the accompanying drawing:

Fig. 1 is a plan view of a safety-pin holder constructed in accordance with my invention;

Fig. 2 is a sectional view on the line 2—2 15 of Fig. 1;

Fig. 3 is a sectional view on the line 3—3 of Fig. 1; and

Fig. 4 is a perspective view of the holders- 20 plate detached.

In carrying out my invention, I employ a strip 10 of sheet metal, and struck inward from one side are hooks 1 and 12 and in the opposite side with hooks 13 and 14. Struck outward between the hooks 11 is a lug 15, and 25 between the hooks 12 is a similar lug 16; between the hooks 13 is a lug 17 and between the hooks 14 is a lug 18. A safety pin 19 has its body-bar 20, which carries a guard 21, set 30 into the hooks 11 and inside the lug 15, which

places a tension thereon, and another mounting pin, corresponding to the pin 19, will be connected with each of the other pairs of hooks, and onto the pin portion 22 of each mounting pin other pins 23 (usually five) 55 are threaded, so that each pin-unit comprises six pins. The hooks 12 and 13 are spaced nearer together than the hooks 11 and 14 to provide for different sizes of pins.

This holder is readily struck from sheet 60 metal and the pins are readily mounted thereon and may be as readily removed therefrom.

I claim:

1. A safety-pin holder comprising a strip 65 of metal having reversely-turned hooks struck out from its opposite edges, and a lug arranged between each pair of hooks and combined with pins bearing in said hooks and interlocked therewith by said lugs.

2. A safety-pin holder comprising a strip 70 of metal having a pair of spaced hooks projecting outwardly from one face of the said strip, the strip also formed with a lug projecting outwardly between said hooks combined with a safety-pin bearing in said hooks 75 and interlocked therewith by said lug.

In testimony whereof, I have signed this specification.

ALBERT HAGEL.
